CARBURETOR

Eugene Rivoche, Washington, D. C.

Application August 11, 1949, Serial No. 109,787

5 Claims. (Cl. 261—44)

1

This invention pertains to a metering device and, more particularly, to carburetors for regulating and controlling the supply of the air-fuel mixture to internal combustion engines and the like.

It is an object of this invention to provide a carburetor provided with one or more adjustable jets adapted for use with the same or different fuels, and adapted to be simultaneously or serially used.

Another object of the invention is to provide the carburetor for an internal combustion engine wherein there can only be a full synchronization in the mixture of air and fuel, in desired and easily adjustable proportions of air and fuel.

Another object of the invention is to provide a carbureting or metering device for an internal combustion engine wherein the carburetor acts not only as a carburetor, but also may be utilized as a mixer of fuels of different character.

Another object of the invention is to provide a carburetor for an internal combustion engine which operates under pressure supplied by the usual fuel pump and not only by aspiration of the engine.

Another object of the invention is to provide a carburetor which does not utilize a float, thus there is no reservoir of liquid adjacent the engine which could be ignited accidentally.

Another object of the invention is to provide a carburetor wherein the adjustment thereof can be effected while the internal combustion engine with which it is associated is in operation.

Another object of the invention is to provide a carburetor which may be adjusted at any time permitting adjustments for differences in temperature, differences in pressure, or differences in grade of fuel, all such adjustments being possible while the engine is in operation.

Another object of the invention is to provide a carburetor for an internal combustion engine which permits an easy adjustment and quick control of fuel consumption, whereby the internal combustion engine associated therewith can be operated as economically and efficiently as possible, and wherein the utmost performance can be attained, all such adjustments being possible while the engine is in operation.

Another object of the invention is to provide a carburetor which is positive of operation whereby it causes the engine with which it is associated to start immediately, whether the temperature is low or not, and regardless of the aspiration of the engine, and one wherein there is no dependence upon fuel level, and wherein

2

there is always a proper mixture of air and fuel.

Another object of the invention is to provide an inexpensive, easily operated, adjusted and repaired carbureting device for an internal combustion engine which will operate in any position of such device.

Another object of the invention is to provide a carbureting device for an internal combustion engine which is so constructed and arranged that 10 overly large quantities of fuel cannot be supplied to the engine so there can be no flooding of the engine, nor can there be any vapor lock, and there is no danger that the unburned part of the fuel will mix with the lubricating oil or be dangerously expelled from the exhaust.

Another object of the invention is to provide a carburetor which is so constructed and arranged that it is self-cleaning, yet is easily regulated even while the engine is in operation.

20 Another object of the invention is to provide a carburetor for an internal combustion engine wherein a jet, or a plurality of jets, is provided which can be so adjusted as to provide, in effect, an infinite number of selected sized jets.

25 Another object of the invention is to provide a carburetor which is so constructed and arranged that a plurality of different fuels may be mixed in the carburetor for the supply to an internal combustion engine, the amount of such fuels being selectively variable.

30 Another object of the invention is to provide a carburetor wherein not only the supply of fuel can be varied during operation of the engine, but the richness and composition of the air fuel mixture can be varied.

35 Another object of the invention is to provide a carburetor so constructed and arranged that it is readily interchangeable with engines of different size within a reasonable range, of course, the only substantial essential being one of adjustment.

40 Another object of the invention is to provide a carburetor so constructed and arranged that gradual, even acceleration can be attained throughout the entire speed range.

45 Another object of the invention is to provide a carburetor so constructed and arranged that the fuel inlet as well as the air inlet can be composed of unmatched parts, or unmatched parts may be used in both inlets to obtain the desired operational results.

50 Another object of the invention is to provide a carburetor so constructed and arranged that fuel inlets are utilized which may come into operation at different degrees of throttle opening to act as an acceleration pump or to act to help maintain

the speed attained by operation of the accelerator pump until the whole inertia is overcome and the associated engine is in regular high speed ratio condition.

With these and various other objects in view, the invention consists of certain novel features of construction and operation as will be more fully described and particularly pointed out in the specification, drawings and claims appended hereto.

In the drawings which illustrate embodiments of the device and wherein like reference characters are used to designate like parts—

Figure 1 is an elevation, partly in section, of one form of carburetor embodying the invention;

Figure 2 is an enlarged, fragmentary elevation of the inner end of the injection or nozzle members of the carburetor illustrated in Figure 1;

Figure 3 is an end elevation of the orifice illustrated in Figure 2 showing the relative position of the ports for nozzle members illustrated in Figure 1;

Figure 4 is a sectional elevation through the nozzle members illustrated in Figures 1 to 3, inclusive, the same being taken substantially in the plane as indicated by the line 4—4 of Figure 1;

Figure 5 is a fragmentary, sectional elevation of a modified form of carburetor embodying the invention;

Figures 6 and 7 are fragmentary, sectional elevations of modified forms of injection members for carburetors embodying the invention, Figure 7 showing associated injection members having a modified form of air flow control for the fuel supply through said injection members;

Figure 8 is a fragmentary, sectional elevation of another modified form of air flow control of the fuel supply of a carburetor embodying the invention;

Figure 9 is a fragmentary, sectional elevation of a vacuum control device for controlling the fuel cut-off of injection members in a carburetor embodying the invention;

Figure 10 is a fragmentary, sectional elevation of an acceleration vacuum control device for a carburetor embodying the invention;

Figure 11 is a fragmentary, sectional elevation through a modified form of injection members for carburetors embodying the invention, illustrating control means for the air supply during idling position of the carburetor;

Figure 11a is a perspective elevation of an agitating device for use in place of a part of the device shown in Figure 11;

Figure 12 is a fragmentary, sectional elevation of a form of control device for controlling the fuel supply, as from the supply pump to the carburetor injector of a carburetor embodying the invention, the same showing the valves in open position, that is, in a position where acceleration is taking place;

Figure 13 is a fragmentary, sectional elevation corresponding to Figure 12 but showing the inlet valve in closed position, that is, the engine is stopped and the fuel flow is cut off.

Figure 14 is a sectional elevation corresponding to Figure 12 wherein the inlet valve is open but the valve controlling acceleration is closed, that is, the device is in idling position;

Figure 15 is a sectional elevation through a still different form of carburetor embodying the invention, wherein the fuel and air supply control means are operative about a common axis, the section being taken substantially in the plane as indicated by the line 15—15 of Figure 16;

Figure 16 is a sectional plan view taken substantially in the plane as indicated by the line 16—16 of Figure 15;

Figure 17 is a fragmentary, side elevation of the carburetor illustrated in Figures 15 and 16, particularly showing the air inlet control;

Figures 18 and 19 are perspective elevations of forms of cylindrical air valves for carburetors embodying the inventions; showing different forms of air openings to obtain disproportionate air inlets upon proportionate operation of said valves; and,

Figures 20 and 21 are modified forms of disk valves adapted to be substituted for the conventional disk valve used in many conventional carburetors for controlling the air inlet in the same manner as the valves shown in Figures 18 and 19 control the air inlet in the herein disclosed carburetor.

Referring first of all, more particularly, to the form of carburetor illustrated in Figure 1, said carburetor includes a stationary casing 30 having a flange 32 adapted to be connected to the inlet manifold of an internal combustion engine.

Casing 30 is provided with the mixture outlet passage 34 adapted to conduct the mixed air and fuel from mixing chamber 36 to the inlet manifold, and mixing chamber 36 also communicates through intake passage 38 to the atmosphere as through a suitable air filter (not shown). Passages 34 and 38 are preferably substantially cylindrical, the axes thereof being coextensive, i. e., if a section is taken through either passage in a plane normal to the axis, it is circular. Casing 30 is provided with the cylindrical bore 40 in

which the cylindrical air control valve 42 is rotatably mounted, the axis of said bore and air valve being normal to the common axis of passages 34 and 38. Inasmuch as valve 42 is cylindrical, the mixing chamber 36 is directly within said valve. The end of valve 42 is provided with the inlet orifice or port 44 adapted to register with the air intake passage 38, and said valve 42 is also provided with the outlet orifice or port 46 adapted to similarly register with the mixture outlet passage 34.

The ends of the cylindrical valve 42 are closed by the end closure webs 48 and 50 of the outer injection or nozzle members 52 and 54, the axes of which are disposed on the axis of the valve 42, the ends of said outer injection members, which project within the mixing chamber 36, terminating in spaced relation to each other, being substantially frustoconical.

Web 48 and 50 are fastened to the cylindrical valve 42 in such a manner that they can be changed in their relative positions with respect to the cylindrical valve so that they can be disposed in different positions, as for example positions disposed 90° apart for the purpose to be later described. In order to rotate the cylindrical valve 42 and to rotate the outer nozzle members 52 and 54 to vary the positions of the (air) inlet and (mixture) outlet ports 44 and 46 with respect to passages 38 and 34, respectively, a suitable lever 56 is fixedly secured to one of the outer projections 58 or 60 (shown 58) of the outer nozzle members 52 or 54.

The outer nozzle members are threaded as at 70 62 and closure caps 68 and 70 are threaded to the respective outer nozzle members pressing spring 72 between the adjacent cap and the spring seat or shoulder 74 on the inner stationary nozzle or injection member 76 (and 78). Nozzle member 76 (and 78) is connected to a suitable source

of fuel supply through a supply pump (not shown), the inner nozzle members being provided with a fuel passage 98 adapted to be connected through port 82 to the outlet side of said supply pump. Adjustment means as described particularly in applicant's application Serial No. 18,439, filed April 1, 1948, for Carburetor, may be provided for adjusting port 82 as from the dash, or for adjusting inner nozzle member 76 (78) and consequently, the injection ports to be later described. Such adjustment may be made as for varying the operating mixtures where the nozzles inject the same or different fluids. Also, where nozzles are to be used selectively alone, or together.

The outer end 84 of the inner nozzle member is closed by means of the cap 86 provided with a suitable gland or stuffing box 88 through which the valve stem 90 passes. The inner end 92 of the inner nozzle member 76 (78) is frustoconical, being adapted to be of complementary shape to the frustoconical inside portion of the outer nozzle member 52 (54) disposed within the mixing chamber. The inner end 92 of the inner injection members is provided with port 94 which communicates with the frustoconical end 96 of passage 98, passage 98 communicating with port 82. Port 94 is adapted to be controlled by the needle valve 100 secured to stem 90, the position of said valve 100 being controlled by said stem. Stem 90 may be adjusted at cap 86 or remotely adjusted as through a flexible shaft to the dash.

The inner end 92 of the inner injection member is also provided with ports 102, shown as four in number, disposed substantially 90° apart (Figure 4), said ports 102 communicating with passage 98. Ports 102 and 94, as shown, are of substantially circular section. The selected one of the ports 102 is adapted to communicate with the elongated port 104, which, as shown, is disposed in a plane which is at an angle (not 90°) to the axis of the injector members, or in effect, said port is contoured to control the opening and closing of port 102 in the desired manner to obtain the desired gasoline supply from passage 98 to the mixing chamber 36. The operative port 102 which is controlled by port 104 is determined by the positioning of web 48 (50) in its selected position on valve 42.

Port 94 is controlled by one of the contoured ports 106, which ports 106 are shown as four in number (Figure 3), the operative one of said ports with respect to port 94 being determined by the selected position of web 48 (50) on valve 42. It will thus be appreciated that the position of webs 48 and 50 with respect to the valve 42 determines which port 106 controls port 94, and, also, which port 102 is controlled by port 104.

In order to control the air inlet to the mixing chamber 36, valve 42 is rotated, whereby port 44 controls the passage of air through passage 38 to said mixing chamber. The same rotation also controls the flow of the mixture from the mixing chamber 36, through port 46, passage 34 to the manifold. As the valve is rotated the outer injection members are also rotated simultaneously, which controls the passage of fuel from passage 98 through ports 94 and 106 to the mixing chamber 36. The contour of ports 106 is such that the operative port 106 controls the passage of fuel to the mixing chamber, through port 94 in such a manner as to maintain the selected air-fuel ratio. This is accomplished because the designed contour of the operating orifice 106 is such that it opens the designed disproportionate

amount for a proportionate opening of the air intake port, even though the air valve and the outer injection members are moved together (proportionately) and in this way there is a compensation for the difference in velocity between the air and supplied fuel as the throttle is moved. With this construction having once been selected, the selected air-fuel ratio is maintained at any R. P. M. of the engine.

10 Port 104 is positioned so that it starts to open (operative) port 102 when air valve 42 is in a predetermined position, and port 102 is in maximum open position at the time that the air valve is in its maximum open position, at which time port 94 (106) is in its maximum open position. Ports 102, 104, 94 and 106 are so relatively positioned with respect to the air valve that at the time acceleration is initiated an enriched mixture is supplied to the manifold independent of 15 the velocity of the air, because the ports are so positioned and shaped that an additional amount of fuel is supplied to the mixing chamber through ports 94 and 106 at the time acceleration is initiated. This additional supply of fuel normally 20 causes an enriched mixture to be supplied to the manifold, which causes acceleration, but as the speed of the engine increases, and inasmuch as the gasoline supply through the port 94 is not increased with the increase of speed of the air 25 velocity due to the increase in speed of the engine, the air-fuel ratio tends to return to the selected air-fuel ratio. However, port 102 having been opened by port 104 during the opening 30 of the air valve during accelerating operation, 35 said port 102 (104) supplies an additional amount of fuel which maintains the enriched air-fuel ratio during the entire accelerating range.

Referring now to the modification illustrated in Figure 5, the carburetor comprises the casing 108 (similar to casing 30), said casing having the securing flange 110 adapted to be secured to a manifold of an internal combustion engine, and is provided with the cylindrical bore 112 (similar to bore 40) for accommodating the cylindrical air control valve 114. Valve 114 is provided with the air inlet port 116 and the mixture outlet port 118, said ports communicating, respectively, with the air inlet passage 120 (similar to passage 38) adapted to be connected through a suitable filter (not shown) to the atmosphere, and to the mixture passage 122 (similar to passage 34). As before, the axes of passages 122 and 120 coincide and are normal to the axis of valve 114.

55 The disposition of ports 116 and 118 determine the communication between atmosphere and mixing chamber 124, and between said mixing chamber and the manifold. Only one injection member is illustrated, but it is understood that 60 either only one is adapted to be used, or a plurality may be used such as illustrated in Figure 1. Where only one is used, the radial flange 126 of the cylindrical valve is adapted to be closed by a plain cover plate. Where a plurality are 65 used the construction to be described is provided in duplicate as shown in Figure 1.

The injection assembly, indicated generally as at 128, is disposed on the axis of rotation of the cylindrical air-valve 114, as certain of the injection members rotate therewith. The outer injection member 130 is provided with the radial closure flange or web 132 adapted to be secured to the radial flange 134 of the cylindrical valve and, as before, is adapted to be positioned in four different positions, spaced 90° apart (or other

selected spacing may be used, the number of which spacings determining the number of ports of the injection assembly which communicate with the mixing chamber. The outer injection member is provided with the inwardly directed frusto-conical member 136 having a similar inner bearing surface adapted to have bearing cooperation with a complementary frusto-conical surface 138 of the inner injection member 140. The inner injection member 140 is shouldered as at 142, forming a spring seat for the retaining spring 144, which is interposed between said shoulder and the closure cap 146 threadedly secured to the outwardly projecting member 148 of the outer injection member 130.

The inner injection member 140 is threaded internally as at 150, providing securing means for the threaded projection of base 152 of the bellows housing 154. The upper bellows housing member 156 is threadedly secured as at 158 to base 152. The flexible, collapsible bellows 160, of substantially toroidal form, is disposed within bellows housing 154 displacing a certain volume in said housing, one side of said bellows being secured to the base 152. The inside of said bellows communicates with mixing chamber 124 through passage 162, which passes through a portion of the base member 152 and the inner injection member 140.

Base member 152 and inner injection member 140 are also provided with an axially disposed passage 164 terminating in a valve seat 166 for the needle valve 168. The needle valve is adapted to control the passage 170 (similar to passage 94) communicating with the port 172 (similar to port 106) in outer injection member 136 shaped similarly for the same purpose as port 106. Passage 170 communicates with passage 174 which in turn communicates with a valve passage 176 in which a spring pressed valve 178 is urged toward closed position by means of the spring 180, said valve seating on the seat 182 which controls the passage 184 communicating with the bellows housing externally of the bellows. Valve 178 seats toward passage 184.

Top bellows housing member 156 is provided with the extension 186 threaded as at 188 for the reception of the securing cap 190. Cap 190 serves as a seat for one end of spring 192 seated at the other end on the shoulder 194 of the valve stem guide member 196, said member being provided with the frusto-conical surface complementary to and fitting within the frusto-conical surface 197 provided on the extension member 186.

Housing 154 is provided with the boss 193 which in turn is provided with the valve housing 200 within which is disposed the spring pressed valve 202 seating on seat 204, being urged toward closed position by means of the spring 206. Valve 202 controls passage 208 communicating with a source of fuel supply, and the inside of said housing 200 communicates through passage 210 with the inside of the bellows housing 154 externally of the bellows 160. Valve stem 212 of the valve 168 is disposed on the axis of the nozzle and extends outwardly of the stem closure member 196, being provided with means, such as a manual adjusting screw 214 whereby the position of the nozzle valve may be adjusted to control the opening of passage 170.

In the operation of this device a suitable lever, not shown, similar to lever 56 (Figure 1) is provided for rotating the cylindrical valve 114 and the outer nozzle member whereby port 172 is controlled and functions similarly to port 106 (Fig-

ure 1) already described. Fuel will be supplied from the source as by the fuel pump (not shown) and will flow past valve 202 and will fill the bellows housing chamber externally of the bellows 160, and the bellows will be collapsed by the pump pressure plus the vacuum in the mixing chamber acting on the inside of the bellows through passage 162, but the pump pressure plus the suction (vacuum) in the mixing chamber will not be sufficient at this time to open valve 178. When the vacuum decreases within the mixing chamber, the vacuum acting within the bellows 160 through passage 162 will drop, permitting the bellows to expand, whereupon the pressure will increase on valve 178 sufficiently to overcome the spring 180, whereupon a quantity (shot) of fuel will be supplied through passage 174, passage 170 and through port 172 to the mixing chamber, thereby increasing the amount of fuel supplied thereto to be mixed within said chamber and supplied through the port 118 to the manifold through passage 122. The expansion of the bellows will be effective to cause this shot, as fuel will not back up into the supply line when bellows 160 expands as valve 202 will close preventing this backing up.

When the vacuum is again raised within the mixing chamber 124, it will act on the inside of the bellows, through passage 162, causing said bellows to move toward collapsed position, whereupon more fuel is permitted to be supplied past valve 202 to the inside of bellows housing 154 and fuel will be supplied through passage 158 and port 172, in which case valve 178 will be closed. Thus with this device enrichment occurs in somewhat the same manner as where a separate pump is actuated for acceleration purposes but in this case the enrichment is dependent upon changes in pressures in the engine manifold as a result of changes in the throttle position.

Referring to the nozzle or injection member illustrated in Figure 6, said injection member comprises an outer casing or injection member 216 which is preferably disposed on the axis of the end closure for the air valve such as illustrated in Figure 1, but is non-rotatable. The injection member 216 is provided with the passage 218 communicating with the supply pump connected to a source of fuel supply, the passage terminating in a conical valve seat 220 disposed adjacent the port 222. The valve seat is adapted to be controlled by the needle valve 224 which, in turn, is controlled through stem 226, said stem being controlled manually or through suitable pressure devices such as will be, more particularly described with respect to Figures 3, 9, 10 and 12 to 14. Passage 222 communicates with chamber 228 disposed in the injection member 216 and closed by the closure 230. Closure 230 is provided with the valve seat 232 adapted to be controlled by the valve member 234 controlling the passage of fuel into the mixing chamber.

Valve member 234 is substantially frusto-conical, having a portion disposed outwardly of the chamber 228 and within the mixing chamber 65 where it can be acted upon by the passage of air, and once the valve member is open, by the passage of fluid (air-fuel mixture) passing therethrough. The valve member is so disposed that 70 it is adjacent the mixture outlet passage as 34 in Figure 1, the axis of the valve member extending in the same direction as the axes of passages 34 and 38. Valve 234 within the chamber 228 is contoured as at 236 whereby the port 75 232 is controlled in the same manner as al-

ready described with respect to port 106, Figure 1. Valve 234 is provided with the stem 238 passing through suitable packing 240 so that there can be no leakage around the stem, and extends upwardly, a spring 242 being interposed between injection member 216 and the spring cap 244 secured as at 246 to the stem, urging the valve member toward closed position.

In the operation of this form of device, assuming valve member 234 to be closed, the velocity of the air passing through the carburetor will act on valve member 234, opening said valve member against spring 242, thereby permitting fuel to be supplied past the needle valve 224 and past valve 234 into the mixing chamber. The opening of the valve member will also be aided by the fuel pump pressure. The contour of the valve 234 determines the disproportionate opening of the fuel port as compared to the air flow as was described with respect to Figure 1.

In Figure 7, a valve control is illustrated wherein a plurality of fuel nozzles 248 and 250 are controlled by a single valve 252. As before, these nozzles are disposed on a common axis (coinciding with the axis of the air valve) and project within the combustion chamber but are non-rotatable with respect to the air valve, the axis of the control valve for said nozzles preferably being in the direction of air flow through the carburetor. Each of said nozzle members 248 and 250 comprises a nozzle member 254 provided with a passage 256 communicating with a suitable pump of a source of fuel supply. Each passage is provided with the valve seat 258 adapted to be controlled by the needle valve 260.

Said needle valve 260 is provided with a contoured portion which controls the disproportionate flow of fuel past seat 258. Said needle valve is adapted to be controlled manually, or through suitable operating mechanism such as to be later described with respect to Figures 8, 9, 10 and 12 to 14. Passage 256 communicates with discharge passage 262 through which fuel is supplied to the mixing chamber of the carburetor such as illustrated in Figure 1. Passage 262 is adapted to be controlled by the valve 252 which may be conical in shape (or pear shaped), being urged toward closed position by means of the leaf spring 264 secured at its ends as at 266 to said nozzle members.

In this form of device it is the flow of air and the air fuel mixture aided by the supply pump pressure which controls the opening of valve 252 and, consequently the supply of fuel to the mixing chamber. Valve 252 can be contoured similar to valve 234 (236) in Figure 6, in which case valves 260 need not be contoured, and this determines the disproportionate opening of the fuel ports 262.

Referring now to the form of device illustrated in Figure 8, this device is also adapted to extend within the mixing chamber, or may be in one of the passages to or from the mixing chamber of the carburetor, and is adapted to be controlled by the passage of air or air and fuel mixture through the carburetor. The device comprises the injection member 268 provided with the passage 270, the injection member being stationary with respect to the carburetor housing (casing) and being secured as at 272 to the fuel supply pipe 274 which is adapted to be connected as at 275 to the fuel pump connected to the source of fuel supply.

A spring seat 276 is threaded into the injection member 268 within passage 270 and is suit-

ably apertured as at 278 to permit the passage of fuel therethrough. Passage 270 is provided with the valve seat 280 communicating with the inlet passage 282, which in turn communicates with the mixing chamber or one of the passages (as 34 or 38, Figure 1) through the carburetor. Valve seat 280 is normally abutted by the valve 284 to close the inlet passage 282, spring 286 being interposed between the valve and the spring seat 276 urging said valve toward closed position. Valve 284 is provided with the fluted or otherwise suitably shaped stem 288 extending through passage 282 to a point within the carburetor, and the injection member 268 is provided with the bracket 290 to which the actuating member 292 is pivoted as at 294. Actuating member 294 is provided with the contoured cam 296 disposed in engagement with the end of stem 288. This device is preferably disposed so that, in inoperative condition, with valve 284 closed the operating member 292 will extend toward the air flow, i. e., the axis of injection member 268 will be normal to the axes of passages such as 34, and 38 of Figure 1.

In the operation of this device, assuming the air flow to be downwardly as viewed in Figure 8, when the air flow reaches a predetermined amount, operating member 292 will be moved in a counterclockwise direction about pivot 294, causing the cam 296 to depress the stem 288 in accordance with the contour of the cam, opening the valve 284, whereby a disproportionate amount of fuel can be supplied within the carburetor in a manner similar to that supplied through the ports 106 (or 104) as shown and described with respect to Figure 1.

In the construction illustrated in Figures 9 and 10, the fuel supply line 296 is adapted to be connected as to an injector having port supplying fuel within the mixing chamber of a carburetor as through port 94 in Figure 1. However, in Figures 9 and 10 the needle valve, which may be a plain needle valve or a contoured one as shown in Figure 7, may be placed remotely from port 94. Supply line 296 is provided with the valve seat 298 normally abutted by the needle valve 300.

In the modification illustrated in Figure 9 valve stem 302, of the needle valve 300, passes through a suitable stuffing box or gland 304 as in an elbow in line 296, and is secured to the movable seat member 306 disposed in the housing 308. A spring 310 is interposed between the seat member 306 and a seat 312 on the cover 314 of the housing 308, said spring with the bellows 316, urging the valve 300 toward closed position. Flexible, collapsible bellows 316 is secured at one end to the seat member 306 and at the other end to seat member 312, thus being a closed member, the bellows acting in the same direction as the spring, that is, toward valve closing position. The inside of the bellows is connected through pipe 318 to the carburetor, as for example, to passage 34 in Figure 1. Therefore, in the case of Figure 9 the vacuum within the carburetor will tend to collapse bellows 316 and, consequently, tend to open valve 300. Thus a fluctuation in vacuum causes movement of the valve 300 to control the passage of fuel in accordance with the movement of the contour of the valve 300.

In the case of the construction illustrated in Figure 10 the valve stem 302 passes through a stuffing box or gland 320, as in an elbow of the supply line 296, and is secured to bellows end plate 322 as at 324. Stuffing box 320 is in end

11

plate 326 to which one end of the bellows 328 is secured, the opposite end of said bellows being secured to plate 322. Flexible, collapsible bellows 328 is of substantially toroidal shape, and of course, the bellows and end plates may be disposed in a housing such as 308 (Figure 9). The bellows acts in a direction to separate plates 322 and 326, and spring 330 may also be interposed between said plates acting in the same direction, that is, to urge valve 300 toward open position. Pipe 332 is connected at one end to the inside of the bellows 328 and at the other end to the carburetor suction, as to passage 34 (Figure 1). In Figure 10 the vacuum in the carburetor controls valve 300, which may be contoured, or plain, as desired, a rise in vacuum tending to move the valve toward closed position, and a fall in vacuum operating the valve in the reverse direction. Such a form of device might be useful for injecting special fuel components into the engine when the vacuum in the carburetor is low, or as a form of acceleration pump when the vacuum is decreased by a sudden opening of the throttle.

In the device illustrated in Figure 11 there is illustrated mechanism whereby injection means is provided as for a carburetor such as illustrated in Figure 1, and wherein a rotary air valve is used such as air valve 42 in casing 34 (Figure 1). In this case an injector (at one or both sides of the air valve) comprises the outer injection member 334 (similar to injection member 52 (Figure 1), provided with the closure web 336 for closing an end of the air valve, such as valve 42 Figure 1. Said outer injection member is rotatable with the air valve, as described in Figure 1, and is provided with contoured ports 338 and 340, similar to ports 104 and 106. The inner, non-rotatable, injection member 342 is provided with the conical end 344 fitting within the inner conical end of the outer injection member, and is provided with ports 346 and 348, similar to ports 102 and 94, respectively, of Figure 1.

The inner injection member is suitably retained in assembly with the outer injection member, and is provided with the passage 350 for supplying fuel to ports 346 and 348, said passage 350 being closed by cap 352 to which the fuel supply pipe 354 is connected. The fuel supply line is adapted to supply fuel through a suitable pump from the source of supply to the inner injection member. Fuel supply pipe 354 may be controlled as in the case of fuel supply line 296 (Figure 9) by the needle valve and control means therefor. As before pointed out, the control device illustrated in Figure 9 is a control using the engine vacuum, wherein the fuel valve 300 is closed when the engine is inoperative, at which time the fuel supply is cut off from the nozzle. The control device illustrated in Figure 10, while vacuum controlled, is adapted to be operative during acceleration so that, if desired, in the device illustrated in Figure 11, both of the control devices illustrated in Figures 9 and 10 may be used, but where only one is used, that shown in Figure 9 is the one which is used.

An air supply line 356 is disposed axially of the injection assembly, passes through cap 352 through a fluid tight connection, and is secured to its inner end as at 358 to the end of the inner nozzle member 344. A baffle 360 is provided whereby the air supplied through pipe 356 is directed toward port 340. Baffle 360 may be eliminated, and some agitating means may be used in place thereof to facilitate mixing the air and fuel. By way of example, this agitating device may be

12

the propeller 361 pivoted at 363 to shaft 365 which is adapted to be secured to member 344 so that it rotates in the mixing chamber. Other such devices may be used as helices, turbines, paddles, etc. Pipe 356 is provided with the valve seat 362 controlled by the needle valve 364, which is manually adjustable, as is indicated more or less diagrammatically as at 366, but thereafter is controlled by vacuum control mechanism, indicated generally as at 368, which is similar to that shown in Figure 9. This mechanism is vacuum controlled through pipe 370 similar to pipe 318 in Figure 9.

It will thus be seen that in the idling position, the air valve, such as air valve 42 (Figure 1), will be closed but valve 364 will be open, whereby idling air will be supplied within the mixing chamber. In this construction, in idling the air valve port controlling the inlet passage 38 (Figure 1), is closed, and either the valve controlling the passage 34 is eliminated or it is cracked open. As the cylindrical air valve is opened to permit air to be supplied through passage 38 in Figure 1, the vacuum control mechanism operates the control 368 to tend to close the needle valve 364, rendering the air supply through pipe 356 inoperative.

With the device illustrated in Figure 11 when the engine is inoperative, both the air supply and the fuel supply are cut off from the injector. With the conventional carburetor there is provided an air supply opening which is constantly open. Therefore, with the use of the conventional carburetor it is practically impossible to use vacuum controlled fuel cut-off devices which are operative as the engine is being started, as the starter motor does not reciprocate the pistons with sufficient speed to draw the necessary vacuum. Thus there is a tendency for the cut-off valve to remain closed which makes for difficult starting. With applicant's device, just prior to starting by the starter motor, the idling air valve 364 is closed, as is the valve which controls the fuel supply through line 354. Inasmuch as the idling air valve 364, as well as the air control valve 42 (Figure 1) is closed, a vacuum is immediately established, even by the slow starting operation of the starter motor, which causes opening of the air supply valve 364 as well as the fuel supply valve to line 354, thus facilitating the starting operation of the engine. Thus, by the use of the control mechanism 368 in this manner, it is possible to use a vacuum control cut-off device as illustrated in Figure 9 to control the fuel line 354.

In Figures 12 to 14, inclusive, there is illustrated another type of control device for controlling fuel supply from the supply pump to the carburetor injector. This control device utilizes the vacuum as well as fuel supply pressure (supply pump pressure) to aid the opening of the valve controlling the supply line. This device comprises a body 372 closed at its ends as at 374 and 376, said body being provided with the chamber 378 having a valve seat 380 therein adapted to be closed by the valve 382. Valve 382 is secured to one closed end of bellows 384, the other end being closed by means of closure 376.

Vacuum line 386 communicates with the inside of bellows 384 and with manifold vacuum, as for example through passage 34 in Figure 1. Valve 382 is provided with the valve stem 388 extending through passage 390 and is provided with the valve 392 disposed in chamber 394. A fuel inlet supply line 396 communicates with

chamber 378 and with a suitable fuel pressure pump connected to a source of supply. Passage 390 communicates with the fuel line 398, which is connected to the mixing chamber of the carburetor, as through injector members such as illustrated in Figure 1.

Chamber 394 is connected through fuel supply line 408 with the carburetor in order to give an added shot of fuel as is desirable in accelerating, as through a connection to the passage 34 in Figure 1. This additional fuel supply is maintained during the whole period of acceleration, thus creating a special power circuit. Valve 392 permits connection between fuel inlet 396 and line 408 when said valve is open, and when closed on seat 402 cut off connection between inlet 396 and line 408.

In this form of the device when the engine is in idling condition, valve 392 is closed on valve seat 402 and valve 382 is open (Figure 14), being maintained in open position both by the vacuum within the bellows 384, and by the fuel supply pressure of the fuel being supplied through line 396. When the engine is in inoperative condition, valve 382 is closed on its seat 380 (Figure 13). When the engine is started and is in its idling or normal speed position, vacuum acting within the bellows 384 will open valve 382 to a position where valve 392 is closed on its seat 402 (Figure 14). When acceleration takes place, there will be a drop in vacuum within bellows 384 so the valve 382 will move toward closed position, but will not completely close (Figure 12). However, the movement will be sufficient to open valve 392 permitting the shot of fuel desired for acceleration through the line 408, it being understood that fuel is also being supplied through line 398 to the carburetor.

Referring now to the form of device illustrated in Figures 15 to 17, inclusive, the carburetor as illustrated is arranged so that the air valve and the fuel supply valves are disposed on a common axis. This device comprises a base 404 adapted to be secured to the intake manifold of an engine. Base 404 is provided with the passage 406 therethrough for supplying the mixture to the manifold, and is provided with the radial flange 408 to which the fixed outer cylindrical shutter member 410 is secured as at 412. Shutter member 410 is provided with the spaced air openings 414 through which air passes as through filters (not shown). Inner movable cylindrical shutter member 416 is rotatably mounted on bearing surface 418 on flange 408, and said inner shutter member is provided with the air openings 420. Shutter member 416 is secured as at 422 to radial shutter member 424 provided with fixed openings 426 therethrough whereby, in effect, said member 424 is a spider.

Member 424 adjacent the vertical axis of shutters 410 and 416 is provided with the downwardly extending conical wall 428 provided with contoured port 430 therein similar to port 106 (Figure 1). Movable shutter 416 is secured as at 432 to the radial closure member 434 which is provided with the centrally disposed, downwardly extending conical nozzle member 436 provided with contoured openings 438 therein. It will thus be seen that members 424 and 434 rotate with shutter 416. Shutter 416 adjacent the top thereof is provided with a closure 440 secured thereto as at 442, and said cover, adjacent the center thereof, is provided with means for rotating the shutter 416, as by the throttle, which means may take the form of any convenient means, such as

a gear 444 adapted to be rotated by said throttle. It is obvious that radial shutters disposed at the top of the cylindrical housing (Figs. 15 and 17) of the carburetor could be substituted for the cylindrical shutter members 410 and 416.

Upper, inner injection member 446 extends through said cover plate 440 and is provided with the frusto-conical end 448 matching the upper cone surface of member 436, being maintained in fluid tight relation therewith by means of the spring 450 interposed between said cover plate 440 and the spring seat 452 on injection member 446. A fuel passage 454 is provided in injection member 446 and communicates with passages 456 controlled by ports 438. Lower, inner injection member 458 extends through injection member 446 and has a nozzle end 460 having a conical surface matching the inner conical surface of nozzle member 428. Injection member 458 is maintained in fluid tight relation to nozzle member 428 by means of spring 462 interposed between end member 458 and nozzle member 436. Nozzle member 458 is provided with the fuel passage 464 communicating with passage 466, which is controlled by port 430. Port 430 is preferably also contoured in the same manner and for the same purpose as port 106 in Figure 1. In operation of this form of the device, it will be seen that the air openings 414 and 420 are controlled by rotation of shutter member 416 which at the same time controls the openings of ports 438 and 430, thus causing a functioning similar to that described with respect to the relation of ports 106 and 104 and the air ports in Figure 1.

In the form of carburetor illustrated in Figure 1, for example, the cylindrical air valve 42 is provided with ports 44 and 46. These ports control flow from passage 38 into the mixing chamber 36, and from the mixing chamber into intake manifold through passage 34. It is convenient in manufacture for passages 38 and 34 to be circular in section. Ports 44 and 46, which control passages 38 and 34 by their position with respect thereto, may be of the selected shape so that a proportional movement of the cylindrical valve gives a disproportionate effective opening. Examples of such ports are illustrated in Figures 18 and 19 wherein the cylindrical valves 468 and 470 are provided with such ports 472 and 474, respectively. The configurations of the ports are chosen to give the desired disproportionate opening.

In carburetors such as illustrated in the patent to Moorehouse No. 920,979, operation of the throttle causes a circular air inlet to be controlled by a circular closure which is rotated around a center spaced from the center of the air inlet. Thus a proportional movement of the throttle causes a proportional opening or closing of the air inlet. In order to cause a disproportionate opening or closing of the air inlet, devices such as illustrated in Figures 20 and 21 may be substituted for the circular closure of Moorehouse, which controls the circular air inlet. In Figure 20 there is shown a circular disk 476 utilized to completely close the air inlet. This is associated with a contoured disk 478 so shaped that as it moves over the air inlet a disproportionate amount of inlet opening is obtained for a proportionate movement of the throttle. Each of the disks 476 and 478 are adapted to be pivoted through suitable connected arms 480 to the throttle control.

A modified form of closure structure is illustrated in Figure 21. In this figure the outer

closures 482 and 484 are provided with different contoured openings and the inner disk 486 is adapted to conform to the shape of the air inlet for closing said inlet. Said disks may be pivoted through arms 488 to the accelerator control means, and the accelerator may be selectively connected as at 490 and 492. In this form of air inlet control the center closure 486 is selectively used with either of the closures 482 or 484. And in each of the structures shown in Figures 20 and 21 the contours of the contoured disks is chosen in the same manner as the openings in the construction shown in Figures 18 and 19.

It is to be understood that this application is not to be limited by the exact embodiments of the device shown, which are merely by way of illustration and not limitation as various and other forms of the device will, of course, be apparent to those skilled in the art without departing from the spirit of the invention or the scope of the claims.

For example, although only two injection members have been shown and described in the embodiments illustrated, it is obvious that any desired number of such injection members could be similarly incorporated.

I claim:

1. In fuel metering mechanism for an internal combustion engine, the combination of a casing having an outlet adapted to be connected to the fuel mixture inlet of an internal combustion engine, said casing having an air inlet, the casing having a cylindrical bore, a cylindrical valve member rotatably mounted in said bore and provided with ports for controlling flow through said casing outlet and inlet, said rotary valve member and casing forming a mixing chamber, closures for the ends of said casing, one of said closures being rotatable and connected to said valve member, an injection device disposed on the axis of said valve member and extending into the mixing chamber, said injection device comprising an outer injection member fixed to said rotatable closure and having its axis disposed on the axis of said valve member, the nozzle end of said injection member being disposed in said mixing chamber, a second injection member mounted in said outer injection member and having a nozzle end extending into the nozzle end of said outer injection member, said outer injection member being non-rotatable with respect to said cylindrical valve member, said nozzle ends having fuel ports for controlling the passage of fuel to said mixing chamber, said outer injection member having a plurality of similar contoured ports spaced apart equidistantly and of varying shape and disposed in a plane normal to the axis of said valve member, said outer injection member being a single port in a plane at an angle to the axis of said valve member, the entrance of the single port being disposed adjacent the end one of the contoured ports, said inner injection member having a single port of substantially circular section adapted to be controlled by the selected one of said contoured ports whereby a disproportionate opening of said last named single port is effected by a proportionate rotation of said cylindrical valve member and said outer injection member, said inner injection member having a plurality of equally spaced ports of substantially circular section in a plane normal to the axis of said circular valve member, the selection of said last

named ports being controlled by said first named single port, rotation of the outer injection member rotating the valve member to vary the casing inlet and outlet and also rotate the ports of the outer injection member with respect to the ports of the inner injection member to vary the supply of fuel to said mixing chamber, and throttle means for simultaneously rotating the outer injection member and said valve member, rotation of the outer injection member and said valve member serving to regulate the fuel ports with respect to the casing inlet and outlet to maintain a selected air-fuel ratio during the entire operation of the throttle means.

2. In fuel metering mechanism for an internal combustion engine, the combination of a casing having an outlet adapted to be connected to the fuel mixture inlet of an internal combustion engine, said casing having an air inlet, said outlet and air inlet comprising coaxial passages of substantially circular section, the casing having a cylindrical bore, the axis of which is substantially normal to the axis of said passages, a cylindrical valve member rotatably mounted in said bore and provided with ports for controlling flow through said casing outlet and inlet, said ports being contoured other than circular, said rotary valve member and casing forming a mixing chamber, closures for the ends of said casing, one of said closures being rotatable and connected to said valve member, an injection device disposed on the axis of said valve member and extending into the mixing chamber, said injection device comprising an outer injection member fixed to said rotatable closure and having its axis disposed on the axis of said valve member, the nozzle end of said injection member being disposed in said mixing chamber, a second injection member mounted in said outer injection member and having a nozzle end extending into the nozzle end of said outer injection member, said inner injection member having a closed end, and closing the end of said outer injection member within said combustion chamber, said outer injection member being non-rotatable with respect to said cylindrical valve member, said nozzle ends having fuel ports for controlling the passage of fuel to said mixing chamber, said outer injection member having a plurality of similar contoured ports spaced apart equidistantly and of varying shape and disposed in a plane normal to the axis of said valve member, said outer injection member having a single port in a plane at an angle to the axis of said valve member, the entrance of the single port being disposed adjacent the end one of the contoured ports, said inner injection member having a single port of substantially circular section adapted to be controlled by the selected one of said contoured ports whereby a disproportionate opening of said last named single port is effected by a proportionate rotation of said cylindrical valve member and said outer injection member, said inner injection member having a plurality of equally spaced ports of substantially circular section in a plane normal to the axis of said circular valve member, the selected of said last named ports being controlled by said first named single port, rotation of the outer injection member rotating the valve member to vary the casing inlet and outlet and also rotate the ports of the outer injection member with respect to the ports of the inner injection member to vary the supply of fuel to said mixing chamber, and throttle means for simultaneously rotating the outer in-

jection member and said valve member, rotation of the outer injection member and said valve member serving to regulate the fuel ports with respect to the casing inlet and outlet to maintain a selected air-fuel ratio during the entire operation of the throttle means.

3. In fuel metering mechanism for an internal combustion engine, the combination of a casing having an outlet adapted to be connected to the fuel mixture inlet of an internal combustion engine, said casing having an air inlet, said outlet and air inlet comprising coaxial passages of substantially circular section, the casing having a cylindrical bore the axis of which is substantially normal to the axis of said passages, a cylindrical valve member rotatably mounted in said bore and provided with ports for controlling flow through said casing outlet and inlet, said rotary valve member and casing forming a mixing chamber, closures for the ends of said casing, one of said closures being rotatable and connected to said valve member, an injection device disposed on the axis of said valve member and extending into the mixing chamber, said injection device comprising an outer injection member fixed to said rotatable closure and having its axis disposed on the axis of said valve member, the nozzle end of said injection member being disposed in said mixing chamber, a second injection member mounted in said outer injection member and having a nozzle end extending into the nozzle end of said outer injection member, said outer injection member being non-rotatable with respect to said cylindrical valve member, said nozzle ends having fuel ports for controlling the passage of fuel to said mixing chamber, said outer injection member having a plurality of similar contoured ports spaced apart equidistantly and of varying shape and disposed in a plane normal to the axis of said valve member, said outer injection member having a single port in a plane at an angle to the axis of said valve member, the entrance of the single port being disposed adjacent the end one of the contoured ports, said inner injection member having a single port of substantially circular section adapted to be controlled by the selected one of said contoured ports whereby a disproportionate opening of said last named single port is effected by a proportionate rotation of said cylindrical valve member and said outer injection member, said inner injection member having a plurality of equally spaced ports of substantially circular section in a plane normal to the axis of said circular valve member, the selected of said last named ports being controlled by said first named single port, rotation of the outer injection member rotating the valve member to vary the casing inlet and outlet and also rotate the ports of the outer injection member with respect to the ports of the inner injection member to vary the supply of fuel to said mixing chamber, and throttle means for simultaneously rotating the outer injection member and said valve member, rotation of the outer injection member and said valve member serving to regulate the fuel ports with respect to the casing inlet and outlet to maintain a selected air-fuel ratio during the entire operation of the throttle means.

4. In fuel metering mechanism for an internal combustion engine, the combination of a casing having an outlet adapted to be connected to the fuel mixture inlet of an internal

combustion engine, said casing having an air inlet, the casing having a cylindrical bore, a cylindrical valve member rotatably mounted in said bore and provided with ports for controlling flow through said casing outlet and inlet, said rotary valve member and casing forming a mixing chamber, closures for the ends of said casing, one of said closures being rotatable and connected to said valve member, an injection device disposed on the axis of said valve member and extending into the mixing chamber, said injection device comprising an outer injection member fixed to said rotatable closure and having its axis disposed on the axis of said valve member, the nozzle end of said injection member being disposed in said mixing chamber, a second injection member mounted in said outer injection member and having a nozzle end extending into the nozzle end of said outer injection member, said outer injection member being non-rotatable with respect to said cylindrical valve member, said nozzle ends having fuel ports for controlling the passage of fuel to said mixing chamber, said outer injection member having a plurality of similar contoured ports spaced apart equidistantly and of varying shape and disposed in a plane normal to the axis of said valve member, said outer injection member having a single port in a plane at an angle to the axis of said valve member, the entrance of the single port being disposed adjacent the end one of the contoured ports, said inner injection member having a single port of substantially circular section adapted to be controlled by the selected one of said contoured ports whereby a disproportionate opening of said last named single port is effected by a proportionate rotation of said cylindrical valve member and said outer injection member, said inner injection member having a plurality of equally spaced ports of substantially circular section in a plane normal to the axis of said circular valve member, the selected of said last named ports being controlled by said first named single port, rotation of the outer injection member rotating the valve member to vary the casing inlet and outlet and also rotate the ports of the outer injection member with respect to the ports of the inner injection member to vary the supply of fuel to said mixing chamber, an air supply line extending through said inner injection member and communicating with said mixing chamber, a baffle for directing the air from said last named supply line toward the operative of said first named contoured ports, a valve in said supply line operative when said cylindrical valve member is inoperative to admit air to the mixing chamber, and throttle means for simultaneously rotating the outer injection member and said valve member, rotation of the outer injection member and said valve member serving to regulate the fuel ports with respect to the casing inlet and outlet to maintain a selected air-fuel ratio during the entire operation of the throttle means and rendering the valve controlling the air supply line inoperative.

5. A fuel metering device in accordance with claim 1 wherein there is a control device comprising a casing having spaced chambers separated by spaced valve seats, a connection from one of said chambers to the outlet of said carburetor, a connection between said seats to said injection device, a connection from the other chamber to a source of fuel pressure supply, a collapsible bellows in said last named chamber having one

end connected to the carburetor outlet whereby suction tends to collapse said bellows, the other end of said bellows being connected to a valve having valve members adapted to close one of said seats, when the bellows is in collapsed condition the valve closing communication between the first named chamber and the fuel inlet, the bellows in fully extended position causing said valve to close communication between the fuel inlet and each of the other connections to the carburetor, the valve in intermediate position causing communication between each of said chambers.
